(57) **CLAIM**

The ornamental design for a display screen or portion thereof with graphical user interface, as shown and described.

DESCRIPTION

FIG. 1 is a front view of a first embodiment of a display screen or portion thereof with graphical user interface; and, FIG. 2 is a front view of a second embodiment thereof.

The evenly spaced broken lines at the outer perimeter of the drawings depict a display screen or portion thereof and form no part of the claimed design.

1 Claim, 2 Drawing Sheets

FIG. 1

FIG. 2
